US00D893437S

(12) **United States Design Patent** (10) **Patent No.:** **US D893,437 S**
(45) **Date of Patent:** ** *Aug. 18, 2020

(54) **CONTROL DEVICE**

(71) Applicant: **Lutron Technology Company LLC**,
Coopersburg, PA (US)

(72) Inventors: **Chris Dimberg**, Easton, PA (US);
Susan Hakkarainen, Doylestown, PA
(US); **Jason C. Killo**, Emmaus, PA
(US); **Brad Michael Kreschollek**,
Bethlehem, PA (US); **Noel Mayo**,
Philadelphia, PA (US); **Matthew Philip
McDonald**, Phoenixville, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/680,802**

(22) Filed: **Feb. 20, 2019**

Related U.S. Application Data

(63) Continuation of application No. 29/633,233, filed on
Jan. 12, 2018, now Pat. No. Des. 846,508, which is a
continuation of application No. 29/569,814, filed on
Jun. 30, 2016, now Pat. No. Des. 814,428.

(57) **CLAIM**

The ornamental design for a control device, as shown and
described.

DESCRIPTION

FIG. 1 is a front perspective view of a control device
showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines illustrate structure or features
which form no part of the claimed design.

In FIGS. 1-6, the thick, solid black lines depict surfaces
having the contrast in appearance as shown.

1 Claim, 4 Drawing Sheets
